OVERWRAPPED CIGARETTE CARTON

James R. Chapman, Jeffersontown, Ky., assignor to Reynolds Metals Company, Richmond, Va., a corporation of Delaware

Application May 15, 1957, Serial No. 659,238

5 Claims. (Cl. 229—51)

This invention relates to an overwrapped carton for cigarettes, or the like. More particularly, it relates to an overwrapped carton which may be readily opened and reclosed without impairment of the sales appeal furnished by the overwrap material and without requiring time consuming precautions by the operator.

As is known, a special packaging problem is presented in the marketing of cigarettes in certain localities wherein local taxes are imposed thereon. In general, the manufacturer of cigarettes operating on a nation wide basis and employing high speed cartoning and packaging equipment, pays the Federal tax and affixes to each package of cigarettes the Federal stamp on which such tax has been paid. These packages bearing such stamps are then enclosed in a conventional carton about which a suitable overwrap is affixed and this completed carton then moves in trade channels. However, upon entering a State or locality in which a local tax is also imposed, it is necessary for the wholesaler or distributor to open the carton, remove each package, and affix to that package an additional stamp or other symbol indicative of payment of that local tax. After this is accomplished, the packages are restored to the carton which then is placed on the retailer's shelf and becomes the article found at the point of sale.

Usually, the above described re-stamping operation is conducted manually and involves a greater or lesser mutilation not only of the overwrap, but also the carton, unless time consuming precautions are taken by the operator. It has further been found that much of the sales appeal of attractive overwrap material designed to attract discriminating trade is lost as a result of these limitations of the described business practice. Accordingly, it is an object of my invention to provide a means for overcoming these and similar disadvantages now found in the retailing of cigarettes and other commodities having similar problems. I have discovered that, by employing a modified conventional cigarette carton with a closely fitting heat-sealed overwrap thereon, the required restamping operation can be carried out quickly without detracting from the sales appeal of the carton.

An object of the invention is to provide a readily openable and reclosable cigarette carton having an overwrap heat-sealed thereto and which is not mutilated objectionably during the opening and reclosing of the carton.

Another object is to provide an overwrapped cigarette carton having a projection integral with the carton material and governing the adhesion of the overwrap to the carton in a selected region adapted for initiating the opening of the closed carton.

Another object is to provide an inexpensive overwrapped cigarette carton which may be opened rapidly without objectionable mutilation of either the overwrap material or of the carton material.

Other objects and advantages will become more ap-

2

parent as the description proceeds and when considered in conjunction with the accompanying drawing in which Fig. 1 is a perspective view of an overwrapped carton prior to being opened, the overwrap being shown diagrammatically by solid lines.

Fig. 2 is a perspective view of the overwrapped carton in opened position.

Fig. 3 is a sectional view through the closed carton on an enlarged scale and taken along line 3—3 of Fig. 1.

10 Fig. 4 is a fragmental sectional view of the upper edge of the closed carton taken along line 4—4 of Fig. 1.

Fig. 5 is a sectional view to a greatly enlarged scale of a preferred form of overwrap material for the carton; and

15 Fig. 6 is a fragmental view similar to Fig. 3 and showing a modified form of flap.

Referring first to Fig. 5, there is shown generally at 10 an overwrap of the general type disclosed in the patent to Farrell et al., 2,430,459 and which is suitable

20 for use with my invention. I prefer, in particular, to use the thin wrapping material known by the trademark, Keyseal, comprising an aluminum foil layer 11 laminated with a microcrystalline wax layer 12 to an inner layer 13 of tissue paper. Such an overwrap may be readily 25 sealed to the carton surfaces by conventional heat-sealing means and the layer 11 may bear printed matter in attractive designs, which adds to the sales appeal of the carton. In addition, such an overwrap may be neatly severed along a given line without objectionable tearing.

30 Considering now Figs. 1 and 2, a conventional cigarette carton formed of paper board may be encased by the above described heat sealable overwrap at the factory and be shipped in sealed condition to the State wherein an additional tax is to be levied. This carton is made 35 from a single sheet of paper board or equivalent material and comprises a bottom panel member 14, coacting front and rear side panel members 15 and 16 and has opposite ends, one being shown at 17, consisting of flaps which extend from the panel members and which are permanently glued together to form the ends. The top panel member 18 is pivoted to the rear panel member and has an elongated flap 19 at its front extremity. This flap is adapted to fit snugly against the inner surface 40 of the front panel member while the carton is in closed position, and in contrast to known cartons of this type, does not require adhesive to hold the carton in shape.

45 As will thus be seen, an overwrapped carton of parallelepiped shape with well defined straight edges at the junction of the top panel member 18 and at the 50 ends and front wall of the carton is provided. However, in applying the heat-sealed overwrap, the close fit between the top panel member and the ends and front wall of the carton, as well as the opacity of overwrap 10, normally renders those lines of separation between these 55 respective parts indistinguishable, and thus, the operator is unable to determine the precise point at which to insert a tool for opening the carton. It will be understood that, in its broader aspects, any conventional overwrap, such as cellophane, polyethylene and the like, 60 may be used and that some of these overwraps are transparent. However, due to the manner in which such overwraps are applied by machine, the parting line between the top and front of the carton usually is difficult to detect and this has further contributed to the mutilation of the overwrap and carton, regardless of whether 65 the overwrap is opaque or transparent, during the opening procedure.

70 With the foregoing in mind, reference is made to Fig. 3 showing a significant feature of the present invention. For the purpose of controlling adhesion of the overwrap to the carton at a predetermined region along an edge

of the carton, I provide a projecting portion of the carton blank which serves to space the flap 19 and the front wall panel 15 apart. Accordingly, when the overwrap is applied to the carton, an open slot 20 is left beneath the overwrap material which bridges that slot. Since the bridging portion of overwrap 10 does not adhere to any portion of the carton blank, it may be easily punctured with a knife blade or other tool in order to start the slitting action necessary to open the carton. In general, a single projection 21, as shown in Figs. 1, 2 and 3, is sufficient and may be formed merely by pressing a member against the outer surface of front panel 15 to provide an embossed dot as shown. This forming operation can readily be incorporated into conventional packaging machinery and, as will be seen, the projection is formed as an integral portion of the carton and requires no additional carton blank material. As an alternative form, the projecting portion may be formed in the flap 19 as seen at 22 in Fig. 6 and wherein a similar slot 23 is formed.

It is contemplated that the overwrap will be provided with suitable reference indicia, particularly when formed of an opaque material, to show the location of slots 20 or 23. Such a slot may be formed either at the right hand upper corner or at the left hand upper corner of the front of the carton, provided all cartons to be handled have the slot at the same corner. When opening the overwrapped cartons, the operator merely slips a knife blade into the slot and draws the blade lengthwise of the carton between the abutting front panel 15 and the surface of flap 19. As noted in the preferred embodiment shown in Fig. 4, no obstruction to the movement of the blade is present, since these parts are not glued together. Of course, several glue spots may be used, if desired, without departing from the scope of the invention. Moreover, the slots generally are only a fraction of an inch in length, being long enough to start the blade in the proper direction, but not so long as to leave a substantial length of bridging overwrap which might contribute to bulging of the closed carton.

After the front of the overwrap is slit, the ends are similarly slit and the front panel section is lifted, as seen in Fig. 2, to provide access to the cigarettes. After the restamping operation, the front panel is again lowered and may be glued to the flap 19. If desired, the top panel may be the one selected for lifting. At this time, the advantages of the invention are most apparent. The overwrap which is heat-sealed to the surfaces of the carton is found to be un torn, merely being neatly slit in three straight lines, and the carton retains substantially all of its original sales appeal. The above steps of slitting, opening, stamping, glueing and reclosing lend themselves readily to a simple machine operation.

Having thus described the invention and having shown a preferred embodiment thereof, it will be understood that numerous changes may be made in the construction without departing from the spirit of the invention and it is, therefore, desired that the present embodiment be considered in all respects as illustrative and not restrictive, reference being made to the appended claims rather than to the foregoing description to indicate the scope of the invention.

What I claim as new and desire to secure by Letters Patent of the United States is:

1. In an overwrapped cigarette carton adapted to be opened and reclosed by manual operation, said carton being formed of a single blank of material and having a bottom panel member, coacting front and rear side panel members, opposite ends consisting of flaps which extend from said members and with said flaps being permanently glued together to form said ends, and a top panel member pivoted to said rear side member and having an elongated flap at the extremity thereof adapted to be inserted interiorly of said front panel member and in close contact therewith, and a closely fitting overwrap contacting the exterior surfaces of said carton on each of said panel members and ends; the improvement comprising a projection integral with said blank of material and located at an upper corner of the front of said carton, said projection having a depth sufficient to space in a predetermined region a portion of said elongated flap from the adjacent portion of said front panel member thereby to prevent the contact of said overwrap with said carton in said region and to form a slot bridged by said overwrap in order that a tool may be inserted through said bridging overwrap into said slot for neatly severing the overwrap during the opening of said carton.
2. A carton as defined in claim 1 wherein said projection is formed integrally with said front panel member.
3. A carton as defined in claim 1 wherein said projection is formed integrally with said elongated flap.
4. A carton as defined in claim 1 wherein said overwrap is heat-sealed to the surfaces of said carton.
5. A carton as defined in claim 4 wherein said overwrap comprises an aluminum foil laminated by a microcrystalline wax to a tissue paper layer adapted to contact the surfaces of said carton.
